LIFT TRUCK

Warner K. Brown, Battle Creek, Mich., assignor to Clark
Equipment Company, a corporation of Michigan

Filed Sept. 12, 1963, Ser. No. 76,568

Term of patent 14 years

(Cl. D14—3)

FIG. 1

FIG. 2

FIG. 3

The dominant features of my design reside in the portions illustrated in solid lines. The side opposite that shown in FIGS. 1 and 2 is a mirror image thereof.

I claim:

The ornamental design for a lift truck, as shown and described.
